ATTORNEYS.*

UNITED STATES PATENT OFFICE.

HARRY W. NEAL, OF INDIANAPOLIS, INDIANA.

LOCKING DEVICE FOR COIL-BOXES AND SWITCHES.

1,262,378.

Specification of Letters Patent.

Patented Apr. 9, 1918.

Application filed December 21, 1916. Serial No. 138,271.

To all whom it may concern:

Be it known that I, HARRY W. NEAL, a citizen of the United States, residing at Indianapolis, in the county of Marion and State of Indiana, have invented certain new and useful Improvements in Locking Devices for Coil-Boxes and Switches, of which the following is a specification.

This invention relates to certain means for locking the coil-boxes and switches, controlling the electric circuits in automobile construction, against impertinent or felonious tampering.

The object of the invention, in addition to the locking the coil-box and circuit control switch against unauthorized tampering, is to prevent temporary connections being made between the coils and high tension cables, for shunting the electric current around the switch with impertinent or felonious intent.

A further object of the invention consists in the provision of a device of the above character which will be simple in construction, efficient in operation and which will be cheap to manufacture.

I accomplish the above objects of the invention, and such others as will appear from a perusal of the specification and claims, by means of the construction illustrated in the accompanying drawings, forming a part hereof, in which—

Figure 1 is a side elevation of a conventional style of a coil-box employed in automobile construction, showing the housing for inclosing the switch, in section. Fig. 2 is a fragmentary detail in front elevation of the coil-box, showing my invention in operative position. Fig. 3 is a top or plan view of the construction shown in Fig. 2. Fig. 4 is a cross section on the line 4—4 in Figs. 1 and 2. Fig. 5 is a face view of switch, the remaining structure being omitted. Fig. 6 is an edge view of the switch shifting blade interposed between the key and switch. Fig. 7 is a front view of the blade shown in Fig. 6. Fig. 8 is a rear elevation of the blade shown in Figs. 6 and 7. Fig. 9 is a cross section of the blade on the line 9—9 in Fig. 8. Fig. 10 is a perspective view of the invention in an assembled condition, the coil-box being omitted.

Referring to the drawings, 15 represents a conventional style of a box comprising two separate parts for housing the induction coils within the electric circuits in automo-

bile construction, and 16 the case for inclosing the movable parts of the switch. The case 16, for convenience, is preferably mounted upon the front side of the box 15. Fig. 5 of the drawings shows a preferred style of a switch in which the blade 17 is shifted through the oscillation of shaft 18 to close the circuit between switch-points A and B, or A and C, depending upon the direction in which blade 17 is shifted. Switch case 16 is generally provided with a face-plate but in applying my invention this plate is removed, leaving the movable parts of the switch exposed, as shown in Fig. 5.

In the application of my invention, I provide a housing 20, which conforms somewhat to the contour of case 16, for inclosing said case 16. Upon the front face of housing 20 I form an integral sleeve 19 for housing the tumblers of a cylinder lock of any usual or suitable construction. With the insertion of the proper key 21 the latter is free to oscillate a cylinder 22 which in turn oscillates a flat bar 23. Bar 23 engages a slot 24 in shifting plate 25 and the latter carries a disk 26 which is provided with the lugs 27 which engage the recesses 28 in the end of shaft 18. By means of this construction blade 17 of the switch is shifted by the manipulation of key 21.

Housing 20 is retained in position upon the face of box 15 and the box is locked by means of a metal strap comprising as its first member a strap-section 30 having one end 31 bent at right angles to its body and adapted to project into housing 20 where it is secured from the inside of the housing by means of a screw 32, the position of screw 32 being such as to render it inaccessible from the outside of housing 20. Section 30 extends upward along the front surface of box 15 and thence across the top to the back edge of the latter where the section is cut away to provide a tongue 33 having its outer end bent into a hook 34. Hook 34 is projected through a slot 36 in the second section 37 of the strap and hooks over that portion of section 37 above said slot, whereby the two sections are secured together against accidental displacement when the lower end of section 37 is made fast. I dispense with a permanent hinged connection between sections 30 and 37 for the reason that the right angle end 31 could not be passed between box 15 and dash-board on vehicles already in use without disturbing box 15, and this

have no desire to do. However, I desire to have it understood that I contemplate a permanent connection between these two sections when my device is installed on vehicles during their course of manufacture. Section 37 extends vertically along the rear wall of box 15 and is provided near its lower end with a slot 38 into which is projected a tongue 39 formed on one end of section 40 forming the third section of the strap. Tongue 39 is bent around the metal of section 40 between slot 38 and the end of said section so that a permanent hinged joint is effected at this point. The opposite end of section 40, from that end containing tongue 39, is bent at right angles to its body to form a locking-tongue 42 which is projected into a slot 44 in box 15. Locking-tongue 42 is provided with an aperture 45 which registers with a threaded aperture 46 in a brace-plate 47 permanently fixed inside box 15, and by means of a screw 48 locking-tongue 42 is permanently secured to plate 47. The insertion and removal of screw 48 is effected through an aperture 50 located in the face of housing 20, and to prevent the removal of this screw 48 and the removal of the device from the box 15 and switch with felonious intentions, when the vehicle is left unguarded, is one of the chief features of my invention and will now be described.

It has heretofore been mentioned that plate 17 of the switch is shifted by key 21 through the introduction of a shifting-plate 25, and this plate is of sufficient length to overlap aperture 50 when plate 17 of switch stands in neutral position shown in Fig. 5. Key 21 can be introduced and removed only from the lock when the switch plate 17 is standing in neutral position so that shifting-plate 25 seals aperture 50 when the key is removed and the vehicle is left standing unguarded. After key 21 is inserted into the lock a quarter turn of a revolution of the key is sufficient to shift plate 17 of the switch to close the desired electrical circuit. It will be understood that when the key is given a quarter turn sliding-plate 25 is moved a like distance and renders screw 48 accessible through aperture 50. The opera-

tor is required however to return key 21 to normal position before the electric circuit can be broken, at which time the shifting-plate 25 is again moved to seal aperture 50 and render screw 48 inaccessible. 55

Having thus fully described my said invention, what I desire to secure by Letters Patent, is—

1. The combination, with an induction coil-box and switch, of means for closing said switch, a key for actuating said switch, means extending circumferentially around said box and permanently secured at one end within said box, means for detachably securing the other end of said circumferential means within said box for holding the two parts of the box together, and means rendering the detachable securing means inaccessible when the key is removed. 65

2. The combination, with an induction coil box and switch, of means for incasing said switch, a key for actuating said switch, means extending circumferentially around said coil-box for holding the two parts of said box together and having one end rigidly secured and the other end detachably secured inside the switch incasing means, and independent means actuated by the key for rendering the secured end of the circumferentially extending means inaccessible when the switch stands in neutral position. 70

3. The combination with an induction coil-box and switch, a case for closing said switch and having an aperture leading therein, a key for actuating said switch, a strap passing circumferentially around said box and having one end attached within the box, means for detachably securing the other end of said strap, said securing means being accessible through said aperture, and means actuated by the key for closing said aperture and rendering said detachable strap securing means inaccessible when the switch stands in neutral position. 85

In witness whereof, I have hereunto set my hand and seal at Indianapolis, Indiana, this 14th day of December, A. D. one thousand nine hundred and sixteen. 95

HARRY W. NEAL. [L. S.]
